US00D828231S

(12) **United States Design Patent** (10) **Patent No.:** **US D828,231 S**
(45) **Date of Patent:** **** Sep. 11, 2018**

(54) **ELECTRIC BICYCLE**

(71) Applicant: **ZHEJIANG RIGHT DIGITAL TECHNOLOGY CO., LTD.**, Zhejiang (CN)

(72) Inventor: **Ming Yan**, Zhejiang (CN)

(73) Assignee: **ZHEJIANG RIGHT DIGITAL TECHNOLOGY CO., LTD.**, Zhejiang (CN)

(**) Term: **15 Years**

(21) Appl. No.: **29/584,165**

(22) Filed: **Nov. 11, 2016**

(30) **Foreign Application Priority Data**

May 13, 2016 (CN) 2016 3 0178269

(51) **LOC (11) Cl.** **12-11**

(52) **U.S. Cl.**

USPC **D12/111**

(58) **Field of Classification Search**

(57) **CLAIM**

The ornamental design for an electric bicycle, as shown and described.

DESCRIPTION

FIG. 1 is a front view of the claimed design;
FIG. 2 is a left side view of the claimed design;
FIG. 3 is a right side view of the claimed design;
FIG. 4 is a rear view of the claimed design;
FIG. 5 is a top view the claimed design;
FIG. 6 is a bottom view of the claimed design; and,
FIG. 7 is a perspective view of the claimed design.

1 Claim, 5 Drawing Sheets

FIG. 1

FIG. 2

FIG. 3

FIG. 4

FIG. 5

FIG. 6
